(57) **CLAIM**

The ornamental design for a cartridge, as shown and
described.

DESCRIPTION

FIG. 1 is a perspective view of the cartridge showing of our
new and ornamental design;

FIG. 2 is an alternate perspective view thereof;

FIG. 3 is top view thereof; and,

FIG. 4 is a bottom view thereof.

The portions of the cartridge shown in broken lines shown
in the figures attached hereto form no part of the claimed
design. The unshaded surfaces immediately adjacent to the
broken lines depict portions of the cartridge that form no part
of the claimed design. Front, rear, and side views of the
cartridge are not provided because these views only show
portions of the cartridge that form no part of the claimed
design.
